UNITED STATES PATENT OFFICE.

JOHN G. SEELIG AND JOSEPH B. BARLOW, JR., OF RIPON, WISCONSIN.

DESIGN FOR A TUB.

43,728.

Specification for Design.

Patented Mar. 18, 1913.

Application filed December 14, 1912. Serial No. 736,850. Term of patent 14 years.

To all whom it may concern:

Be it known that we, JOHN G. SEELIG and JOSEPH B. BARLOW, Jr., citizens of the United States, and residents of the city of Ripon, in the county of Fond du Lac and State of Wisconsin, have invented a new, original, and ornamental Design for Tubs, of which the following is a specification, reference being had to the accompanying drawing, forming part thereof.

In the drawing: Figure 1 is a perspective view of a tub showing our new design. Fig. 2 is a top plan view of a tub showing our new design.

We claim:—

The ornamental design for a tub as shown.

JOHN G. SEELIG.
JOSEPH B. BARLOW, JR.
